Christie LLP(57) **CLAIM**

The ornamental design for a vehicle light, as shown and described.

DESCRIPTIONFIG. 1 is a perspective view of the vehicle light;
FIG. 2 is another perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines in the drawings depict portions of the vehicle light that form no part of the claimed design.
